UNITED STATES PATENT OFFICE.

JOHN C. LOOK, OF SAN JOSÉ, CALIFORNIA.

CAR-COUPING.

SPECIFICATION forming part of Letters Patent No. 474,090, dated May 3, 1892.

Application filed January 19, 1892. Serial No. 418,588. (No model.)

To all whom it may concern:

Be it known that I, JOHN C. LOOK, a citizen of the United States, residing at San José, in the county of Santa Clara and State of California, have invented a new and useful Improvement in Car-Couplings, of which the following is a specification.

The object of my invention is to construct a car-coupling of the flat pivoted hook-head class, commonly known as the "vertical plane," in such a way as to make it automatic under all conditions, both as a coupler and buffer, without further attention than to set or let go a handle at the side of the car, to reduce to a minimum the breakage incident upon coupling and buffing, and to make it more efficient in drawing by keeping the hooks fully interlocked at all times.

Briefly stated, my invention consists of a draw-bar having a flat rotary hook-head pivoted in one side and a buffer-arm extending out on the other side, as in draw-bars of this class. A yielding inner guard-bar is made opposite the pivoted hook and is pivoted on the buffer-arm of the draw-bar in such a way that it has a lateral and rearward movement. This guard-bar is acted on by another bar, which is pivoted to the draw-bar back of the buffer-arm and may be called the "equalizing pressure-bar," and this equalizing-bar is acted on by another bar pivoted to the car underneath, with the outer end resting free in a stirrup, so as to give the part that extends out from the car a limited lateral movement, and is actuated by a spring whose power is transmitted through it to the inner guard-bar, which is pivoted to the buffer-arm, and through the buffer-arm to the governing of the draw-bar. A spring also acts on the back of the draw-bar to keep it in against the guard-bar. A locking device is provided within the draw-bar to lock the pivoted hook-head and a chain and bar extending to the side of the car for unlocking the coupler. Cushioning-springs of the usual form are provided for the rear of the draw-bar, with draw-plates and other fixtures of the usual mode.

In the drawings, Figure 1 represents two cars furnished with my couplings coupled together, the draw-bar of one car being in section on line x of Fig. 2 and the draw-bar of

the other car partly in section on the same line. Parts of both cars are broken out to show all the connections. Fig. 2 is a side view without the outer guard-bar, the buffer-arm 55 being in section on line x' of Fig. 4 and the equalizing-bar broken off at about x^2 , Fig. 4. Fig. 3 is a front view. Fig. 4 is a plan view showing two cars coming together with both hooks closed. Fig. 5 is a plan view showing 60 the position taken by the guard-bars when coupling. Fig. 6 is a plan view showing two cars buffing. Fig. 7 is a plan view showing a coupling to be made when one coupler is left open and one closed, the one closed being of 65 another type. Fig. 8 is a plan view showing two cars coming together when both couplers are open. Fig. 9 is a plan view showing two cars buffing on a curve. Fig. 10 is a plan view showing two cars drawing on a curve. Fig. 11 70 shows a locking-pin for the coupler on car 2 in Fig. 1. Fig. 12 shows the pivoting of the spring-actingguard-bar, taken on line x^3 , Fig. 1.

A is the draw-bar.

B is the inner guard-bar.

75

C is the outer guard-bar.

D is the equalizing-bar.

E is the pivoted hook-head.

F is the locking mechanism.

The draw-bar A, as shown, is preferably 80 made in cast metal and is of the shape and size to be inserted in the ears of the ordinary construction. The draw-bar on car 1, Fig. 1, is in section on the line x of Fig. 2. The walls $a a$ connect the top and bottom parts and 85 leave a space between for the locking mechanism. On one side of the draw-bar extend the jaws $a' a'$. (See Fig. 3.) Between these jaws is pivoted the rotary hook, the pin a^2 passing through the jaws and the hook E. On 90 the other side of the draw-bar extends out the buffer-arm a^3 . This buffer-arm is flat on its buffing-face and is joined to the jaws $a' a'$ by the incline a^4 . The shank a^5 extends back under the car and has jaws which are pivoted at a^6 to the rod s , that goes through the cushioning-spring s' . The head of this spring-rod is flat and extends transversely to fill up 95 the space between the draft-irons s^3 .

The hook-head E is of the pattern usual in 100 this class, and the lock-lever e is of a similar type, but follows the incline a^4 , as shown.

This lock-lever e is held closed by the pawl F , pivoted in the buffer-arm a^3 and acted on by the spring n , pressing on the cam f , the spring being made fast to the draw-bar at n' , 5 as shown. A bar f' extends out from the pawl, to which the chain l is fastened. The chain goes back through a guide l' and then connects to a bar l^2 , which runs through guide to the side of the car and has a notch 10 l^3 to catch into the outer guide l^4 to hold it when keeping the coupler unlocked. This locking device will unlock the coupling automatically should the draw-bar become detached at its rear end by the chain pulling 15 back the pawl F , and will then hold the draw-bar from dropping on the track.

Another device is shown in car 2, Fig. 1, and the front elevation of the same is shown in Fig. 3. It consists in a rectangular hole 20 r in the draw-bar and dropping in the vertical locking-bolt R . (Shown in Fig. 11.) To uncouple with this device, the bolt is raised up to where the lock-lever e will pass under the offset r' shown in the bolt. With this 25 form of gravity-lock the lock-lever e has a tail-piece e' , made integral with it and forming an arc of a circle with a^2 as the center. This tail-piece extends out through the draw-bar head when coupled, as shown in Fig. 1, 30 car 2, and when uncoupled, as in Fig. 7, car 2, it stops under the offset in the locking-bolt, and will not let it drop until the pivoted head has reached its proper place.

A device is also shown for raising the gravity-bolt. It is shown best in Fig. 3, also in Fig. 1, car 2. The pivot-pin b' in the guard-arm has an elbow b^2 , which extends out laterally far enough to make a suitable fulcrum for a bar i , which is pivoted in the end of the 40 elbow. This bar i is divided into two parts, one being on each side of the elbow. The bar then extends across under the locking-bolt, which also passes through the division in the bar and then extends to the side of the coupler, where a chain is attached for lifting purposes. The locking-bolt has two cross-pins r^2 , 45 one above and one below the lifting-bar. The one below is to keep the lifting-bar from dropping off, and the one above is to raise the locking-bolt R when the lifting-bar is raised up, 50 which is shown in dotted lines, Fig. 3. The vertical width of the elbow b^2 is made as shown, in order that the lifting-bar i will have a guide up and down and cannot get twisted 55 out of order. The chain l is fastened to the end of the lifting-bar and passes upwardly through a guide made integral with the draw-bar, and then backwardly through another guide fastened to the car, and then fastened 60 to an operating-bar l^2 , as shown. To uncouple with this combination, the bar l^2 is pulled out and held in a catch. This pulls the chain through the two guides and raises the lifting-bar i , which raises the vertical locking-bolt R . To couple, the bar l^2 is let out of 65 the catch and the bolt drops when the pivoted head is turned to place. An offset r' in the

locking-bolt R may be made inclined, whereby the bolt will have a bearing for the full width in the lower jaw, and yet not be required to 70 be raised so high to let the lock-lever pass under, as the lock-lever will strike the incline and raise the bolt. This device will uncouple automatically should the draw-bar become detached at the rear end by the chain pulling 75 upwardly through the guide on the draw-bar and raising the locking-bolt.

In connection with the hook-head coupling-bar is the inner guard-bar B . This bar has two extending arms b^2 , which slip over the 80 buffer-arm a^3 and are pivoted at b' . This guard then extends straight out from the buffer-arm to a point even with the hook, and then slants outwardly from the hook so as to form a guide to receive the coupler of the opposite car, as seen in Fig. 4, and to form a pocket for the opposite coupling-head when the two are coupled together. A bar D acts on the inner guard B . This bar D is the equalizer and is pivoted in the draw-bar at d . The 85 outer point d' is made to press on the inner guard B . The elbows in it are to make it conform to the recess between the draft-timbers and around the buffer-arm a^3 . The bar D is acted on by the spring-acting outer guard-bar 90 C . This guard-bar C is pivoted to the car underneath, at c , and, as shown in Fig. 12, its outer end is loose in the carry-iron c' to give it a lateral movement, and has an inner stop c^2 and an outer stop c^3 . Out past the carry-iron it is 95 made larger, at c^4 , to suit the space required by the draft-timber which is between it and the draw-bar. The outer point c^5 is about even with the buffer-arm on the draw-bar. A 100 spring c^6 is made fast to the guard-bar at c^7 , and the other end, pressing on the stop c^8 made in the carry-iron, throws the guard-bar 105 toward the inner stop c^2 . On the hook side of the draw-bar is a box g , containing a spring and plunger g' and g^2 . The plunger goes 110 through the draft-timber and presses on the draw-bar and holds it against the guard-bar C . This spring g' is weaker than the spring c^6 on the guard-bar, its duty being merely to assist the draw-bar in following the movement 115 of the outer guard-bar C .

When the coupler is placed in the car, it is made to assume the position, as shown in Fig. 4, to be automatic. This is done by the spring-acting outer guard-bar C pressing the coupling-bar over until the end of the coupling-hook falls near the center line of the car, which is shown in the dotted lines x^4 , Fig. 4. The action of the guard-bar C is made to stop at that point by the inner stop c^2 . When so 120 placed, the draw-head of one coupling comes opposite the pocket and guard of the other coupling, so that the hooks will pass each other. The position of two such in the act of 125 coupling is shown in Fig. 5, the draw-head of each coupling forcing the guard of the opposite coupling outward and rearward in the form of a circle, with the pivot b' as a center. When the hooks have passed each other, the 130

inner guard-bars B press on the backs of the hooks and force them together, as shown in Fig. 1, the draw-bars then being in the center line of the car and the outer guard-bars C in 5 the center of the stirrup c'. Fig. 8 shows both couplers open. Then the end of one hook strikes against the lock-lever e of the other hook and pushes it around into place, as shown in Figs. 6 and 9. In Fig. 7 one is 10 left open and one closed. The one closed is of the solid guard-bar type, and in coupling with that type one must be open.

Fig. 6 shows two cars buffing, in which act 15 the points of the hooks slide down the incline a^4 until the buffer-heads a' strike the buffer-arms a^3 , and in buffing on a curve, as in Fig. 9, but half of such operation takes place—that is, only the buffer-head and buffer-arm 20 on the inside of the curve meet. In either case a^4 the points of the hooks sustain but little shock and are not liable to be broken. In other types of this class the buffing is done largely by the end of the hook. The wall of 25 such other types would be represented by the dotted lines x^5 , Fig. 9. The value of the incline a^4 and square-faced buffer-arm a^3 is also shown in effecting a sure coupling, as will be seen in Fig. 9, where the end of one hook impinges against the incline in the lock-lever e 30 of the other hook, and causes it to be pressed into the proper place, so that both coupling-hooks are turned, one by the end of the hook impinging on the incline and the other by the incline in the lock-lever e being impinged upon. 35 When coupling on a straight track, both impinge and are in turn impinged upon, as in Figs. 1 and 6.

In Fig. 10 cars are shown drawing on a curve. The couplings are nearly straight with 40 each other as they turn on the pivot at the rear end of the draw-bar and swing between the timbers, the one on car 1 leaving its guard-bar and the one on car 2 forcing its guard-bar C to the outer stop, and should the curve be 45 the reverse the reverse would take place in the couplings, so that the draw-hooks are always fully interlocked, with no slipping laterally.

In Figs. 2, 3, and 6 dead-block buffers h 50 are shown, which may be used with this coupling. In Fig. 6 car 2 is represented to be higher than car 1, and the buffer-block of car 1 strikes against the guard-bar B of car 2 and pushes it back out of the way, and the guard-bar B on car 1 passes under the buffer-block on car 2, so that there can be no breakage from the use of buffer-blocks. In Fig. 6 on car 1 is 55 shown another form of guard B, which does not require the intermediate bar D. This 60 form can be used on cars where the cushioning springs s , Fig. 1, is short, so that the draw-bar does not have much longitudinal movement.

The value of the equalizing-bar D is shown 65 in Fig. 10, car 1, where the pressure of the guard-bar C is exerted on the bar D at the point c^5 , and is transmitted from the bar D

to the guard B at the point d' , which is far forward of the pivot b' ; but should the bar D be left out the point c^5 falls opposite the pivot b' , and no pressure is exerted to the outer end 70 of the guard B, and the guard-bar C cannot be extended out any farther, as it would strike the buffer-block of the opposite car.

This coupling can be used on both freight 75 and passenger cars. The drawings here shown of the car-bodies are more intended for freight, except in Fig. 2, where carry-irons such as are used in the passenger car are shown, in order to give a better view to the side eleva- 80

Having thus described my invention, what I claim as new, and desire to secure by Letters Patent, is—

1. In a car-coupling, the combination of a 85 laterally-movable spring-controlled draw-bar having a side projecting buffer-arm, a rotary hook-head pivoted in said draw-bar, a locking and releasing device controlling it, a movable guard opposite the hook and pivoted to the 90 buffer-arm, and a spring-guard attached to the car to press on the movable guard and hold the couplings together and permit their separation sidewise, substantially as herein described. 95

2. In a car-coupling, the combination of a laterally-movable spring-controlled draw-bar having a side projecting buffer-arm, a rotary hook-head pivoted in said draw-bar, a locking and releasing device controlling it, a yielding 100 inner guard opposite the hook-head and pivoted to the buffer-arm, and an independent movable spring-controlled outer guard-bar pivoted to the car and acting on the yielding inner guard to hold the couplings together 105 and permit their separation sidewise, substantially as herein described.

3. In a car-coupling, the combination of a laterally-movable draw-bar having a side projecting buffer-arm, a rotary hook-head pivoted 110 in said draw-bar and having a rearwardly-extending locking-lever arm against which the opposing hook impinges, a locking and releasing device for the hook-head, a movable guard pivoted to the buffer-arm and opposing the 115 hook, and side springs acting on the draw-bar and on the guard to force them toward each other and permit their separation sidewise, substantially as herein described.

4. In a car-coupling, the combination of a 120 laterally and longitudinally movable draw-bar having a hook-head, a movable guard pivoted to the draw-bar opposite the hook-head and separated therefrom, a spring secured to the car and acting on the draw-bar from one 125 side, and a spring secured to the car and acting on the movable guard from the other side to force the draw-bar and guard toward each other and permit their separation sidewise, substantially as herein described. 130

5. In a car-coupling, the combination of a laterally and longitudinally movable spring-controlled draw-bar having a hook-head, a movable inner guard pivoted to the draw-bar

- and opposing the hook, and an independent movable spring-controlled outer guard-bar pivoted to the car and acting on the movable inner guard to press it against the back of the 5 opposing coupling-hook and keep the two coupling-hooks pressed in together and allow said inner guard to follow the longitudinal movement of the draw-bar, substantially as herein described.
10. 6. In a car-coupling, the combination of a laterally-movable draw-bar having a flat-face hook-head, a movable guard pivoted to the draw-bar and opposing the hook, the two constituting a coupling-bar forming a pocket for 15 the opposite coupling-hook, and a spring-guard attached to the car with an innerstop, whereby the coupling-bar is pressed over and held in such a position that the hook-head of the coupling on one car comes opposite the 20 guard and pocket of the coupling of the opposite car when the cars are separated, substantially as herein described.
7. In a car-coupling, the combination of a laterally-movable draw-bar having a hook-head and pivoted guard, said guard being 25 spring-actuated, and an outer stop connected with the car to limit the movement of said guard to a point where the draw-bar can follow it and beyond the point sufficient to permit 30 the said guard to be pressed out for the entrance of the opposite coupling-head, substantially as herein described.
8. In a car-coupling, the combination of a laterally-movable draw-bar with a hook-head 35 and yielding inner guard opposite the hook and pivoted to the draw-bar, an independent laterally-movable spring-controlled outer guard-bar pivoted to the car for acting on the inner guard and draw-bar, and an outer 40 stop to limit the movement of the outer guard-bar to a point where the draw-bar can follow it and beyond the point sufficient to permit the inner guard to be pressed out for the entrance of the opposite coupling-head, substantially 45 as herein described.
9. In a car-coupling, the combination of a laterally-movable draw-bar having a flat-face
- buffer-arm a and jaws a' for a rotary hook-head and an incline a^4 between the buffer-arm and the jaws, a flat-face hook-head pivoted in the jaws and having a locking-lever arm e fitted in a recess in the draw-bar and whose outer edge follows the walls of the incline a^4 in the draw-bar, and a yielding guard opposite the hook-head and pressing against the back of the opposite coupling-hook, all for the purpose of turning the rotary hook to its locking-place and to relieve the end of the hook from the buffing-shock by causing the knuckle to strike the buffer-arm, substantially as herein described.
10. In a car-coupling, the combination of a laterally and longitudinally movable draw-bar with hook-head, a movable guard opposite the hook and pivoted to the draw-bar, a 55 spring-guard attached to the car to act on the movable guard, and the equalizing-bar D , pivoted to the draw-bar back of the movable guard and lying between it and the spring-guard, so that the pressure of the spring-guard transmitted through the equalizing-bar falls at a certain distance forward of the pivot-pin of the movable guard as the draw-bar moves longitudinally, substantially as herein described.
11. In a car-coupling having a pivoted hook-head with locking-lever arm and a gravity-lock for locking the lever, the lifting-bar i , fulcrumed in a projection extending out from the draw-bar, said lifting-bar passing under the gravity-lock and to the opposite side of the draw-bar, a chain attached to the free end of said lifting-bar and passing upwardly through a guide in the draw-bar and thence to an operating lever or bar for the purpose 80 of raising the gravity-lock, substantially as herein described.
- In witness whereof I have hereunto set my hand.
- JOHN C. LOOK.
